UNITED STATES PATENT OFFICE.

MATHIAS HELMBERGER, OF NEW YORK, N. Y.

ATTACHMENT ON SHIPS OR SUBMARINES FOR CUTTING THROUGH WIRE-NETTING.

1,247,111.

Specification of Letters Patent. Patented Nov. 20, 1917.

Application filed March 30, 1917. Serial No. 158,519.

To all whom it may concern:

Be it known that MATHIAS HELMBERGER, subject of the German Emperor, and resident of New York, in the county of New

5 York and State of New York, has invented certain new and useful Attachments on Ships or Submarines for Cutting Through Wire-Nettings, of which the following is a specification.

10 The present invention relates to attachments on ships, particularly submarines, whereby the latter will be safe from entanglement in nettings placed in the path of the ship.

15 With this object in view, my invention consists of means provided on the outside of the ship or submarine, whereby the wires of the netting will be cut through when the ship is thrust against the latter, permitting 20 the ship to pass.

My invention also consists of the combination, arrangement and construction of parts which will be hereinafter fully described and set forth in the appended claims.

25 One embodiment of my invention is illustrated in the accompanying drawing, which forms part of this specification and in which similar reference characters denote corresponding parts, Figure 1 being a top plan

30 view of a ship or submarine, to which the device is shown attached at several points of its fore-part; Fig. 2 is a top plan view of the device proper; Fig. 3 is a vertical section on line 3—3 of Fig. 2 and Fig. 4 is 35 a similar section of the device shown in operation.

Referring specifically to the drawing, *a* denotes the body of the ship or submarine and *b* the device. The device consists of a 40 frame composed of lateral bars *c* which are spaced apart and are rigidly connected to one another by short cross bars such as pins or screws *d* and sleeves *e* mounted thereon; the frame thus constructed is so dimensioned 45 as to be capable of engaging the meshes of a wire netting which is stretched along the coast of an enemy country serving to prevent the passing of a submarine. The frame may have suitable means for its attachment 50 to the body of the ship. In Fig. 1 where the frame is attached to the nose of the ship, the frame is shown as being provided with a forked portion *c'* to engage around the sides of the nose and to be secured thereto by 55 screws or rivets. Where the device is secured to other parts of the ship, the means

for the attachment thereof may be shaped according to the configuration of the part. This frame is adapted to support in itself a suitable cutting mechanism, the function 60 of which will be to cut through the wires forming the meshes of the netting upon the penetration of the frame therethrough. In the present embodiment of my invention, the cutting mechanism is a shear-like affair sub- 65 substantially consisting of two coöperating blades which, on their engagement of a wire of the netting, will be caused to close and thereby sever the wire. To this end the construction is as follows:

70 Slidably guided by two or more of the cross pins *d* of the frame and arranged adjacent and parallel to one of the side bars *c* is a member *f*, having longitudinal slots or recesses *f'* and *f''*. This sliding member *f* 75 is connected to the frame by a coil spring *g* of which one end is secured at *h* to the slide and the other end *h'* to the cross pin *d*. The spring has the tendency to retain the slide in its forward position, shown in Fig. 80 3. Secured to the slide *f*, about midway between its ends, is a plate or block *i* which at one end is provided with an upwardly projecting portion *i'* serving as one of the blades of the cutting mechanism and formed 85 on its forward side with a cutting edge *i''*. The other blade *k* is in form of a lever which is fulcrumed to the blade *i* at *j* and of which the upper part *k'* serves as the blade proper and is formed with a cutting 90 edge *k''* opposite the edge *i''*. Lever *k* is extended to project downwardly and outwardly from the frame and its free end is connected by a pivot *k'* to a link *l*, which is fulcrumed at *l'* to one of the side bars *c* 95 as shown in Fig. 4. This second blade *k* is adapted normally, *i. e.* in inoperative position to extend with its upper part or blade *k'* within the frame or below the upper edges of the bars *c*, *c*, as shown in Fig. 3, 100 but in operative position, to project upwardly or outwardly from the frame as shown in Fig. 4. The blade *i'* on the other hand is adapted to constantly project from beyond the upper edges of the bars *c*, so as 105 to engage a wire of the netting when the frame penetrates or passes through the meshes of the latter. As the ship is thrust against the netting, and the frame passes through one of the meshes of the wire netting, the projecting blade *i'* will engage with 110 its cutting edge *i''* a wire and by the counter-

pressure of the latter, push the member *i* and together with the latter the slide *f*, rearwardly, against the tension of the spring *g* and thereby and through the medium of the link *l*, cause the second blade *k* to swing around its fulcrum *j* so that the cutting edge *k*² will, in coöperation with the cutting edge *i*², engage the wire and sever it.

In practice, it will be necessary to either 10 attach several such cutting devices at different points of the ship's body in order that as the ship continues its motion through the netting, the wires may be cut, enlarging the opening for the passage of the ship. 15 The mechanism may of course, be variously modified in its construction and arrangement without departing from the spirit of my invention and I therefore do not wish to confine myself to the details 20 scribed and shown.

What I claim and desire to secure by Letters Patent is:

1. In a ship or submarine, a wire cutting mechanism supported thereon and comprising 25 a blade capable of yielding longitudinally of the ship's body and projecting away from the latter, and a second blade fulcrumed on the first blade and movably connected at one end to the ship's body so that when the said first blade during the 30 propulsion of the ship under the counter-pressure of a wire of a netting it encounters, yields rearwardly it will cause the second blade to close and in conjunction with 35 the same will perform the cutting operation.

2. In a ship or submarine, a wire cutting mechanism supported thereon and comprising 40 a member capable of sliding longitudinally of the ship's body, a blade fixed to said member and adapted to project away

from the ship's body, a second blade fulcrumed on said first blade and a link connecting said second blade to said ship's body, so that during the propulsion of the ship 45 the first blade under the counter-pressure of a wire of a netting which it encounters, will be moved rearwardly and cause the second blade to close and in conjunction with it will perform the cutting operation. 50

3. In a ship or submarine, a wire cutting mechanism supported thereon, comprising a frame, a sliding member mounted thereon and carrying a blade projecting away from the ship's body, a lever fulcrumed on said 55 blade and formed at one of its ends with a part serving as a second blade and movably connected at its opposite end to the ship's body so that when the first blade is forced rearwardly it will cause the second 60 blade to close and will perform with the latter the cutting operation.

4. In a ship or submarine, a wire cutting mechanism supported thereon and comprising 65 a frame fixed to the ship's body, a member supported in said frame to be capable of moving longitudinally of the ship's body and formed with a blade adapted to project away from the latter, a second blade fulcrumed on said first blade and a link connecting said second blade to the ship's body so that when the first blade is moved the second blade will be caused to close and to 70 perform with the said first blade the cutting operation. 75

Signed at New York city in the county of New York and State of New York this 29th day of March A. D. 1917.

MATHIAS HELMBERGER.
